Fig. 4

UNITED STATES PATENT OFFICE.

ANTHONY L. VISSAT, OF JEANNETTE BOROUGH, PENNSYLVANIA.

RAILWAY FROG.

Application filed August 11, 1926. Serial No. 128,596.

More particularly my present invention relates to that type of railway frogs wherein the interruptions in the fixed rails are completed by means of rail portions carried by 5 a movable frog plate which is shifted in unison with the switch.

Letters Patent of the United States No. 1,231,676 were issued to me on July 3, 1917, for certain improvements in this type of 10 railway frogs, and the present invention comprises further improvements in the same.

Among the objects which I have in view in the present invention are the following.

The improvement of the construction of 15 the movable frog to render the same stronger and more durable.

The provision of means to prevent derailment and avoid injury to the frog mechanism in case a car or locomotive moves out 20 of the closed track.

The prevention of the clogging of the movements of the movable frog plate by the accumulation of dirt.

The provision of means whereby the movable plate may be installed or removed and the connections for shifting the same may be installed, removed or repaired without disturbing the bed plate or the ballast or 25 road bed.

The provision of means for carrying the "blind" drivers of a locomotive over the rail joints of the frog without jumping or jar-ring.

The accomplishment of other important 30 objects will appear from the accompanying description.

In the accompanying drawings, wherein I have illustrated the best embodiment of the principles of my invention now known to me, Fig. 1 is a view in plan of the railway frog, the movable frog plate being positioned to complete the rail of the intersecting track; Fig. 2 is an inverted plan view on enlarged scale of the bed plate and its end 35 castings and also showing the shifting bars of the frog plate; Fig. 3 is a sectional view taken along the line III—III in Fig. 1 illustrating the mounting of the frog plate on the bed plate and the means for shifting the former; Fig. 4 is a top plan view of the bed plate with its end castings dismounted; Figs. 40 45 and 6 are views in plan of the two end

castings; Fig. 7 is a sectional view taken along the line VII—VII in Fig. 1 and showing the assemblage and connections of the 55 various parts, and Fig. 8 is a plan view of the frog showing the frog plate positioned to complete the rail of the tangent track.

Referring to the drawings, the frog structure comprises four main elements, the bed plate 1, the end members 2 and 3 and the frog plate 4. The bed plate is preferably of rolled steel while the end members and the frog plate are preferably castings of hard steel, such as manganese or other suitable 60 alloy.

The frog is supported by the track ties, shown at 5^a, 5^b, 5^c, 5^d, 5^e and 5^f, the bed plate 1 being supported by the ties 5^b, 5^c, 5^d and 5^e, being secured in place by spikes driven 70 through holes, such as 6, in the plate.

One end of the bed plate 1 is provided with an extension 7 having a squared end, and the end casting 2 is undercut at its inner end to overlap inwardly over said extension 75 and has a vertical shoulder 8 which abuts against the end of the latter. Bolts 9 extend down through the casting and extension, and 10 represents one or more squared lugs depending from the casting and snugly fitting 80 the socket holes 11 in the extension to relieve the bolts of strain and torque, and also to facilitate the proper positioning of casting relative to the bed plate.

Likewise the inner end of the other end 85 casting 3 is undercut to overlap the end of the bed plate 1 and the two elements are secured together by the bolts 12, and also by the bottom lug 13 of the casting fitting snugly in the socket hole 14 of the bed plate. 90 The squared end of the bed plate abuts against a vertical shoulder 15 or the under-side of the casting 3.

The outer end of the casting 2 is spiked to the tie 5^a, while the casting 3 is similarly 95 spiked to the tie 5^f.

The heads of the bolts which secure the castings 2 and 3 to the bed plate 1 are spaced between the ties.

16 and 17 are the parallel rails of the tangent track, while 18 and 19 are the parallel rails of the intersecting track, the rails 17 and 18 being interrupted or gapped to allow 100 for the frog structure.

Formed integrally on the end casting 2 are the two rail members 20 and 21 which are alined with the adjacent ends of the track rails 17 and 18, respectively and are in 5 angular relation with each other, merging in a V with a squared apex. The rail members 17 and 18 stop short of the outer end of the casting and the sides of the casting are contoured so that the inner sides of the rail 10 ends 17 and 18 will fit snugly up against the same with their extremities abutting against the rail members 20 and 21. The outsides of the rail members 20 and 21 are contoured similar to the sides of a track rail, so that 15 the standard angle bars 22 may overlap the rail joints on the outside, and bolts 22^a extending through the angle bars and transversely through the casting may be employed to hold the angles and rails rigidly in position, thus securing the rails 18 and 17 in 20 fixed alinement with the rail members of the casting 2.

Similarly the casting 3 is integrally provided with the rail members 23 and 24 which 25 are alined respectively with the adjacent end portions of the track rails 17 and 18. The inner ends of the rail members 23 and 24 are alined respectively with the rail members 20 and 21 respectively, but do not merge with 30 each other at their inner ends, allowing clearance for the travel of the flanged wheels on the rail member 23. The outer ends of the rail members 23 and 24 stop short of the outer end of the casting 3 and the end portions 35 of the rails 17 and 18 fit snug against the sides of the casting 3 and abut against the end of the rail portions 23 and 24, angle bars 25 overlapping the joints on the outside and being bolted in place by bolts 26 extending through the casting.

The movable frog plate 4 is provided with two rail members 27 and 28 in angular relation to each other and so disposed that when the frog plate is shifted into the position shown in Fig. 1, the rail member 28 fills the gap between the adjacent ends of the rail members 21 and 24 and this completes the track rail 18, and when the plate 4 is shifted into the position shown in Fig. 8, the rail member 27 fills the gap between the rail members 20 and 23 and this completes the track rail 17.

The bed plate 1 is provided with a pair of parallel and transversely disposed slotted openings 29 through which extend the lugs 30 depending integrally from the frog plate 4, the lugs being rectangular and sufficiently elongated to form a bearing on the side walls of the slots and thus cause the frog plate to 55 move in proper alinement. The lugs protrude downwardly through the slots and their lower ends are recessed at either side so that the twin connecting bars 31, which have notches to provide clearance for the reduced 60 necks of the lugs, will fit snugly together

with the lugs clamped between them. The twin bars are rigidly yet detachably secured together by the bolts 32 positioned near their opposite ends, so that by sliding the bars, and the frog plate in the proper direction 70 the bolts 32 at either end of the connecting bars may be exposed from beneath the bed plate 1, thus enabling the bolts to be removed and the bars and frog plate dismounted or replaced without disturbing the bed 75 plate or the ballast or road bed.

The ends of the twin bars 31 are prolonged, twisted ninety degrees and turned back over the upper surface of the bed plate, 80 extending to the adjacent edge of the frog plate, thus forming shields or covers 33 for the otherwise exposed ends of the slots 29 as the frog plate moves along the same, thereby preventing the entrance of dirt in the slots which would result in clogging 85 the movement of the frog plate.

On either side of the recessed portions of the bars 31 which engage the lugs 30, the abutting faces of the twin bars are recessed to provide the openings 34 which provides 90 clearance for dirt to drop down out of the slots 29 should such accumulate.

The underside of the frog plate 4 is transversely channelled as shown at 35 to reduce the area of the bearing surfaces in sliding 95 contact and thereby lessen friction.

The fact that the bed plate 1 and the frog plate 4 are of different material, the former of rolled steel and the latter of alloy steel casting, thus providing surfaces of different 100 material reduces the friction and wear of the sliding surfaces.

The straight end of one of the bars 31 of each pair is prolonged, as shown at 31^a, and each is connected by the link 36 to one arm 105 of the bell-crank levers 37 mounted on vertical axis at the side of the track 16—17, the other arms of the levers 37 being connected to the reach rod 38 which extends to the switch mechanism and is operated in unison 110 with the latter so as to shift the frog plate in unison with the switch point.

39 represents a filler member integral with the casting 2 and interposed between the converging rail members 21 and 22 thereof 115 and also extending outwardly to the outer end of the casting 2 between the end portions of the rails 17 and 18. The top surface of the filler is an ascending incline rising to the top level of the rail members 17 and 18 at their apex, and at either side said filler is provided with a relatively shallow groove 40.

The function of this filler is to receive the 120 tread of the "blind" driver or drivers of the locomotive and carry the same along to the frog plate without the usual jarring and jolting. It is understood that the blind drivers usually have a slightly concaved 125 tread with shallow flanges or fins at the 130

sides. The treads of the blind drivers are somewhat broader than those of the flanged drivers and thus a broader treadway provided by the filler 39 furnishes the necessary continuous surface for their travel.

It frequently happens that through either accident or carelessness, a car or locomotive moves out of a closed track, such for instance the track formed by the rails 18 and 19 when the switch is set against it and the movable frog plate occupies the relative position shown in Fig. 8.

Unless special provision be made to take care of such a situation, the moving car or locomotive usually becomes derailed and the frog seriously damaged.

To prevent derailment or damage under such circumstances, I provide means whereby the wheels of the moving car or locomotive will be safely carried over the frog and directed to the proper rail.

Thus the left hand end portions of the rail members 27 and 28 of the frog plate 4 are provided on their adjacent sides with risers 41 and 42, respectively, said risers being integral and gradually inclined portions rising from the end of the plate 4 at the top level of the latter to substantially the top level of the rail members, said risers having a concaved top surface to avoid interference with the flanges of the wheels normally traveling on the rail members 27 or 28.

On the opposite or outer sides of the rail members 27 and 28 I provide the guard rail members 43 and 44, respectively which are inclined upwardly toward the right end of the frog plate and at the end of said plate are of full rail height. These guard rails are so located and disposed that when the rail member 28 is aligned with the rail members 21 and 24 to complete the interrupted rail 18, the guard rail 44 registers with the rail member 23 of the casting 3, as shown in Fig. 1, and when the rail member 27 is aligned with the rail members 20 and 23, completing the interrupted rail 17, as shown in Fig. 8, the guard rail 43 registers with the rail member 24.

Thus with the frog set as shown in Fig. 1, opening the intersecting track 18-19 to the tangent track 16-17 and interrupting the latter, the flanges of the wheels of a car moving from left to right on the rail 17 would engage the riser 42 which would carry the wheels up and diagonally across the rail member 28 and into engagement with the guard rail 44 which the treads of the wheels would mount and thence travel in safety along the rail member 23 to the rail 17.

Again with the frog plate set as shown in Fig. 8 with the tangent track 17-18 open and the intersecting track 18-19 closed, the flanges of the wheels moving toward the frog on the rail 18 would engage the riser

41 and run diagonally across the rail member 27, and the wheel treads would mount the guard rail 43 and be delivered to the rail member 24 and the rail 18. Thus accident would be avoided.

What I desire to claim is:

1. A movable frog for railway tracks comprising a bed plate mounted at the rail crossing, said bed plate being provided with parallel and transversely disposed slots, a movable frog plate mounted on the bed plate and provided with a pair of rail members in angular relation to each other and so disposed that when the frog plate is in one of its positions one of its rail members completes the interruption of one of the fixed track rails and when the frog plate is in its other position its other rail member completes the interruption in the other fixed track rail, said frog plate being provided with depending lugs protruding downwardly through the slots in the bed plate, connections with said lugs for shifting said frog plate, and means for covering the portions of said slots which would otherwise be exposed by the shifting of said frog plate.

2. A movable frog for railway tracks comprising a bed plate mounted at the rail crossing, said bed plate being provided with parallel and transversely disposed slots, a movable frog plate mounted on the bed plate and provided with a pair of rail members in angular relation to each other and so disposed that when the frog plate is in one of its positions one of its rail members completes the interruption of one of the fixed track rails and when the frog plate is in its other position its other rail member completes the interruption in the other fixed track rail, said frog plate being provided with depending lugs protruding downwardly through the slots in the bed plate, connections with said lugs for shifting said frog plate, and means moving with the frog plate for covering the portions of said slots that would otherwise be exposed by the shifting of said frog plate.

3. A movable frog for railway tracks comprising a bed plate mounted at the rail crossing, said bed plate being provided with parallel and transversely disposed slots, a movable frog plate mounted on the bed plate and provided with a pair of rail members in angular relation to each other and so disposed that when the frog plate is in one of its positions one of its rail members completes the interruption of one of the fixed track rails and when the frog plate is in its other position its other rail member completes the interruption in the other fixed track rail, said frog plate being provided with depending lugs protruding downwardly through the slots in the bed plate, connections with said lugs for shifting said frog plate, and means carried by said connections

for covering the portions of said slots that would otherwise be exposed by the shifting of said frog plate.

4. A movable frog for railway tracks comprising a bed plate mounted at the rail crossing, said bed plate being provided with parallel and transversely disposed slots, a movable frog plate mounted on the bed plate and provided with a pair of rail members in angular relation to each other and so disposed that when the frog plate is in one of its positions one of its rail members completes the interruption of one of the fixed track rails and when the frog plate is in its other position its other rail member completes the interruption in the other fixed track rail, said frog plate being provided with depending lugs protruding downwardly through the slots in the bed plate, connections with said lugs for shifting said frog plate, and means for the downward escape of foreign matter from said slots.

5. A movable frog for railway tracks comprising a bed plate mounted at the rail crossing, said bed plate being provided with parallel and transversely disposed slots, a movable frog plate mounted on the bed plate and provided with a pair of rail members in angular relation to each other and so disposed that when the frog plate is in one of its positions one of its rail members completes the interruption of one of the fixed track rails and when the frog plate is in its other position its other rail member completes the interruption in the other fixed track rail, said frog plate being provided with depending lugs protruding downwardly through the slots in the bed plate, connections with said lugs for shifting said frog plate, and means comprising apertures in said connections for the downward escape of foreign matter from said slots.

6. A movable frog for railway tracks comprising a bed plate mounted at the rail crossing, a frog plate mounted on said bed plate and slideable transversely thereof, said frog plate being provided with a pair of rail members in angular relation to each other and so disposed that when the frog plate is shifted into one of its positions one of the rail members completes the interruption of one of the fixed track rails and when the frog plate is in its other position the other of its rail members completes the interruption of the other fixed track rail, and means for dismounting the frog plate from and for mounting the frog plate on the bed plate without requiring access to the under side of the latter.

60 7. A movable frog for railway tracks comprising a bed plate mounted at the rail crossing, a frog plate mounted on said bed plate and slideable transversely thereof, said frog plate being provided with a pair of rail members in angular relation to each other

and so disposed that when the frog plate is shifted into one of its positions one of the rail members completes the interruption of one of the fixed track rails and when the frog plate is in its other position the other of its rail members completes the interruption of the other fixed track rail, connections disposed beneath the bed plate for shifting the frog plate, and means whereby the connections may be installed and removed without requiring access to the under side of the bed plate.

8. A movable frog for railway tracks comprising a bed plate mounted at the rail crossing, a frog plate mounted on said bed plate and slideable transversely thereof, said frog plate being provided with a pair of rail members in angular relation to each other and so disposed that when the frog plate is shifted into one of its positions one of the rail members completes the interruption of one of the fixed track rails and when the frog plate is in its other position the other of its rail members completes the interruption of the other fixed track rail, connections disposed beneath the bed plate for shifting the frog plate, said connections being arranged for installation and removable without requiring access to the under side of the bed plate.

9. A movable frog for railway tracks comprising a bed plate mounted at the rail crossing, said bed plate being provided with transversely disposed and parallel slots, a frog plate mounted on said bed plate and slideable transversely thereof, said frog plate being provided with a pair of rail members in angular relation and so disposed that when the frog plate is shifted into its one position one of the rail members completes the interruption of one of the fixed tracks and when the frog member is shifted into its other position its other rail member completes the interruption of the other fixed track, lugs depending from the frog plate through the slots in the bed plate, pairs of twin bars disposed below the bed plate and gripping the lugs between them, means beyond the ends of the lugs for clamping the bars of each pair together, and connections for said bars for shifting the frog plate.

10. A movable frog for railway tracks comprising a bed plate mounted at the rail crossing, said bed plate being provided with transversely disposed and parallel slots, a frog plate mounted on said bed plate and slideable transversely thereof, said frog plate being provided with a pair of rail members in angular relation and so disposed that when the frog plate is shifted into its one position one of the rail members completes the interruption of one of the fixed tracks and when the frog member is shifted into its other position its other rail member completes the interruption of the other fixed

- track, lugs depending from the frog plate through the slots in the bed plate, pairs of twin bars disposed below the bed plate and clamping the lugs between them, and means 5 for holding the bars in their clamping relation to the lugs, said means being accessible at either side of the base plate for installing or removing the bars without disturbing the bed plate.
- 10 11. A movable frog for railway tracks comprising a bed plate mounted at the rail crossing, said bed plate being provided with transversely disposed and parallel slots, a frog plate mounted on said bed plate and 15 slidable transversely thereof, said frog plate being provided with a pair of rail members in angular relation and so disposed that when the frog plate is shifted into its one position one of the rail members completes 20 the interruption of one of the fixed tracks and when the frog member is shifted into its other position its other rail member completes the interruption of the other fixed track, lugs depending from the frog plate 25 through the slots in the bed plate, pairs of twin bars disposed below the bed plate and clamping the lugs between them, the opposite ends of the twin bars being turned up over the bed plate to cover the portions of 30 the slots which would otherwise be exposed by the shifting of the frog plate.
12. In a movable frog for railway tracks, the combination of a bed plate mounted at the rail crossing, a pair of end members 35 detachably connected to said bed plate and each provided with a pair of rail members in angular relation to each other, said rail members being alined with the ends of the fixed rails of the track, and one of each pair 40 of rail members being alined but spaced from one of the other pair of rail members, a frog plate mounted on the bed plate and slidable transversely thereof, and a pair of rail members on said frog plate and so disposed 45 that when the frog plate is in one of its positions one of the frog plate rail members completes the interruption between two of the rail members of the end members and when the frog plate is in its other position the other frog plate rail member completes 50 the interruption between the other two rail members of the end members.
13. In a movable frog for railway tracks, the combination of a bed plate mounted at 55 the rail crossing, a pair of end members detachably connected to said bed plate and each provided with a pair of rail members in angular relation to each other, said rail members being alined with the ends of the fixed rails of the track, and one of each pair 60 of rail members being alined but spaced from one of the other pair of rail members, a frog plate mounted on the bed plate and slidable transversely thereof, and a pair of rail members on said frog plate and so disposed 65 that when the frog plate is in one of its positions one of the frog plate rail members completes the interruption between two of the rail members of the end members and when the frog plate is in its other position the other frog plate rail member completes 70 the interruption between the other two rail members of the end members.
14. In a movable frog for railway tracks, the combination of a bed plate mounted at the rail crossing, a pair of end members detachably connected to said bed plate and each provided with a pair of rail members in angular relation to each other, said rail members being alined with the ends of the fixed rails of the track, and one of each pair 75 of rail members being alined but spaced from one of the other pair of rail members, a frog plate mounted on the bed plate and slidable transversely thereof, and a pair of rail members on said frog plate and so disposed that when the frog plate is in one of its positions one of the frog plate rail members completes the interruption between two of the rail members of the end members and when the frog plate is in its other position the other frog plate rail member completes 80 the interruption between the other two rail members of the end members.
15. In a movable frog for railway tracks, the combination of a bed plate mounted at the rail crossing, a pair of end members detachably connected to said bed plate and each provided with a pair of rail members in angular relation to each other, said rail members being alined with the ends of the fixed rails of the track, and one of each pair 85 of rail members being alined but spaced from one of the other pair of rail members, a frog plate mounted on the bed plate and slidable transversely thereof, and a pair of rail members on said frog plate and so disposed that when the frog plate is in one of its positions one of the frog plate rail members completes the interruption between two of the rail members of the end members and when the frog plate is in its other position the other frog plate rail member completes 90 the interruption between the other two rail members of the end members.
16. In a movable frog for railway tracks, the combination of a bed plate mounted at the rail crossing, a pair of end members of cast steel detachably connected to the opposite ends of the bed plate and provided with 95

- integrally formed rail members alined with the ends of the fixed track rails and a cast steel frog plate mounted on the bed plate and slidable transversely thereof, said frog 5 plate having integrally formed thereon rail members which are arranged to be brought by the shifting of the plate into alinement with the proper rail members of the end members.
- 10 17. In a movable frog for railway tracks, the combination of a bed plate of rolled steel mounted at the rail crossing, a pair of end members of cast steel detachably connected to the opposite ends of the bed plate 15 and provided with integrally formed rail members alined with the ends of the fixed track rails and a cast steel frog plate mounted on the bed plate and slidable transversely thereof, said frog plate having integrally formed thereon rail members which are arranged to be brought by the shifting of the plate into alinement with the proper rail members of the end members.
18. In a movable frog for railway tracks, 20 the combination of a bed plate mounted at the rail crossing, a frog plate mounted on said bed plate and slidable transversely thereof, said frog plate being provided with a pair of rail members in angular relation, 25 fixed end members at the opposite ends of said bed plate and provided with pairs of rail members arranged to coat with the rail members of the frog plate, and said end members being provided with recessed portions 30 into which the ends of the track rails extend in alinement with the rail members of the end members, and means for securing the rail ends to the end members.
19. In a movable frog for railway tracks, 35 the combination of a bed plate mounted at the rail crossing, a frog plate mounted on said bed plate and slidable transversely thereof, said frog plate being provided with a pair of rail members in angular relation, 40 fixed end members at the opposite ends of said bed plate and provided with pairs of rail members arranged to coat with the rail members of the frog plate, and said end members being provided with recessed portions 45 into which the ends of the track rails extend in alinement with the rail members of the end members, and angle bars for clamping the rail ends to the end members.
20. In a movable frog for railway tracks, 50 the combination of a bed plate mounted at the rail crossing, a frog plate mounted on said bed plate and slidable transversely thereof, said frog plate being provided with a pair of rail members in angular relation, 55 fixed end members at the opposite ends of said bed plate and provided with pairs of rail members arranged to coat with the rail members of the frog plate, and said end members being provided with recessed portions 60 into which the ends of the track rails extend in alinement with the rail members of the end members, and angle bars for clamping the rail ends to the end members.
21. In a movable frog for railway tracks, 65 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members having portions in overlapping relation with the bed plate.
22. In a movable frog for railway tracks, 70 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members having portions in overlapping relation with the bed plate.
23. In a movable frog for railway tracks, 75 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members being provided with portions in overlapping relation to the bed plate and with shoulders bearing against the ends 80 of the bed plate.
24. In a movable frog for railway tracks, 85 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members and the bed plate 90 having portions in interlocking relation.
25. In a movable frog for railway tracks, 95 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members and the bed plate 100 having portions in interlocking relation.
26. In a movable frog for railway tracks, 105 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members being provided with depending lugs which seat in snugly fitting 110 openings in the bed plate.
27. In a movable frog for railway tracks, 115 the combination of a bed plate mounted at the rail crossing, a shiftable frog plate mounted on the bed plate, and end members detachably connected to the opposite ends of the bed plate and provided with rail members in angular relation to each other and alined with the ends of the fixed track rails, said end members having portions in overlapping relation to the bed plate and being 120 also provided with depending lugs seated in snugly fitting openings in the bed plate.
28. In a movable frog for railway tracks, 125 the combination of a bed plate, a frog plate mounted on the bed plate and slidable transversely thereof, a pair of rail members mounted on the frog plate and so disposed that when the frog plate is in one of its 130

positions one of said rail members completes one of the interrupted fixed rails of the track and when the frog plate is in its other position the other rail member completes the other interrupted fixed track rail, and means whereby when wheels enter the frog from one end of the incompletely track said wheels are directed diagonally across the rail member which is in completing position on to the other end of the incompletely track.

27. In a movable frog for railway tracks, the combination of a bed plate, a frog plate mounted on the bed plate and slideable transversely thereof, a pair of rail members mounted on the frog plate and so disposed that when the frog plate is in one of its positions one of said rail members completes one of the interrupted fixed rails of the track and when the frog plate is in its other position the other rail member completes the other interrupted fixed track rail, and risers at the outer side of each rail member to di-

rect wheels entering the frog from an end of the incompletely fixed rail diagonally across said rail member.

28. In a movable frog for railway tracks, the combination of a bed plate, a frog plate mounted on the bed plate and slideable transversely thereof, a pair of rail members mounted on the frog plate and so disposed that when the frog plate is in one of its positions one of said rail members completes one of the interrupted fixed rails of the track and when the frog plate is in its other position the other rail member completes the other interrupted fixed track rail, risers at the outer side of each rail member to direct wheels entering the frog from an end of the incompletely fixed rail diagonally across said rail member, and guard rails on the other side of each of said rail members to deliver said wheels to the proper fixed rail.

Signed at Pittsburgh, Pa., this 9th day of August, 1926.

ANTHONY L. VISSAT.
